UNITED STATES PATENT OFFICE

ERVIN E. LINTZ, OF RENTON, WASHINGTON

COAL-MOVING MACHINE

Application filed February 14, 1930. Serial No. 428,463.

This invention relates to conveyors and the like for conveying material from one level to another.

Another object of the invention contemplates the provision and arrangement of agitators for the conveyor apparatus to keep the material in motion.

An additional object of the invention consists of an operating mechanism for the agitators.

More specifically stated the agitators are connected with the operating mechanism in such manner that the material will be allowed to pass beneath the agitators between strokes whereby continuity of flow will be facilitated.

With the above and other objects in view, the invention further consists of the following novel features and details of construction, to be hereinafter more fully described, illustrated in the accompanying drawings and pointed out in the appended claims.

In the drawings:—

Figure 1 is a fragmentary longitudinal sectional view taken through a trough or sluice showing the present invention as applied for use.

Figure 2 is a fragmentary side elevation of the operating mechanism.

Figure 3 is a longitudinal sectional view taken on line 3—3 of Figure 2.

Figure 4 is a horizontal sectional view taken on line 4—4 of Figure 2.

Figure 5 is a sectional view taken through one of the connections and mounted for the agitators upon the operating mechanism.

Referring to the drawings in detail where-in like characters of reference denote corresponding parts, the reference character 10 indicates generally one side wall of a form of support having a connecting upper wall 11; the initial side wall having a shaft 12 extended therethrough. A pulley wheel 13, mounted upon the outermost end of the shaft 12, is driven by a motor 14 through the employment of an endless belt 15.

An elongated plate, such as indicated at 16, having an annular wall 17 upon one side thereof round at its ends and extending in parallelism at its sides with the adjacent side

edges of the plate 16 proper. A block 18, disposed upon one side of the plate 16 and within the confines of the flange 17, terminates to provide rounded extremities 19 in spaced relation to the curved ends of said annulus. Bolt members 20 passed through the immediate portions of the plate 16 and block 18 also support sleeve members 21 and a retaining plate 22 common to all of the bolt members to prevent displacement of the sleeve members 21. The ends of the retaining plate 22 extends for appreciable distances outwardly and beyond the sleeves 21 and in conjunction with the block 19 provides a raceway 23 within which the teeth 24 of a sprocket gear 25 may be guided for engagement with the sleeves 21. The raceway 26 formed between the adjacent sides of the annulus 17 and the block 18 is provided for a sleeve bearing 27 carried upon a reduced portion 28 of the shaft 12 and by means of which the teeth of the sprocket gear 25 will be aligned for registration with the sleeves 21.

A line shaft generally designated as at L and composed of multiple pipe sections having series of universal joint couplings there-between is designed for reciprocating action with the plate 16 in the following manner.

Attaching plates 29, carried upon opposite sides of the plate member 16 in the manner shown in Figure 3 of the drawings, are curved, as at 30, upon their opposite ends and apertured to accommodate the projecting pintles or trunnions of a saddle plate having engagement with the upper surface 85 and immediate section of the line shaft. A U-bolt arranged upon the aforementioned section of the line shaft has the uppermost projecting ends thereof passed through the saddle plate and nuts or other fastening devices secured thereon whereby the plate 16 and line shaft L will reciprocate in unison. This especial form of connection is adequately illustrated in Figure 5 of the drawings although same is particularly applicable to 95 the agitators about to be described. Said agitators, indicated as at 31, having attaching arms 32 upon opposite sides thereof have their opposite ends upwardly curved and apertured to accommodate the pintles or 100

trunnions 33 of saddle plates 34 having engagement with the under surfaces of the sections of the line shaft L. U-bolts 35 disposed in the manner shown in Figure 5 of the drawings have the depending extremities thereof passed through appropriate portions of the saddle plates 34 and subsequently receive nuts or other fastenings 36 to prevent displacement of the agitator connections with the line shaft.

By this arrangement the agitators induce only their exact weight against the coal or other material passing through the sluice or trough and in the instance of dispensing or delivering coal in lump form therethrough, it is to be noted that the lumps will not be unduly broken or converted into another grade of coal. As the shaft 12 rotates continuously in one direction, it is to be noted that the plate 16 will oscillate with relation thereto incident to the travelling of the sprocket wheel 25 upon opposite sides of the retaining plate 22 and engaging the sleeves 21. The coal or other material travelling through the sluice or trough will be prevented from clogging incident to the shoving action of the agitators about to be delivered thereby from the exact position of the invention in Figure 1 of the drawings.

As an instance of the application of the present invention, it may be stated that the uppermost inclined end of the trough or sluice may be disposed adjacent the working surface or breast of the vein.

The invention is susceptible of various changes in its form, proportions and minor details of construction, and the right is herein reserved to make such changes as properly fall within the scope of the appended claims.

Having described the invention, what is claimed is:

1. A machine of the character described comprising a trough having pushers mounted for oscillatory longitudinal shifting action therein, said pushers being obliquely disposed within the trough and slidably engaged terminally thereof with the bottom wall of the trough, a line shaft, U-bolts carried by the line shaft having saddle plates connected therewith, trunnions projecting from the ends of the saddle plates, and curved attaching arms carried upon the uppermost inclined ends of the pushers having openings in the extremities thereof to rockingly accommodate the trunnions.

2. A machine of the character described comprising a sluice having pushers mounted for longitudinal oscillatory movement therein, a line shaft of sectional formation having universal joint connections therewith, saddle plates mounted upon the sections of the line shaft having trunnions outwardly projecting from the ends thereof, attaching plates carried upon the opposite sides and ad-

70 jacent the uppermost inclined ends of the pushers having registering openings in the remaining extremities thereof to accommodate said trunnions, an operating plate having connection with the line shaft after the manner of the pushers therewith, an annular wall carried by the plate in conformity to the shape of the latter, and an operating mechanism having engagement with the plate and operable within the confines of the annulus. 75

3. A machine of the character described comprising a sluice having pushers mounted for longitudinal oscillatory movement therein, a line shaft of sectional formation having universal joint connections therewith, saddle plates mounted upon the sections of the line shaft having trunnions outwardly projecting from the ends thereof, attaching plates carried upon the opposite sides and adjacent the uppermost inclined ends of the pushers having registering openings in the remaining extremities thereof to accommodate said trunnions, an operating plate having connection with the line shaft after the manner of the pushers therewith, an annular wall carried by the plate in conformity to the shape of the latter, a block carried upon one side of the plate within the confines of and spaced from the adjacent walls of the annulus, sleeve members carried at intervals along the length and outwardly projecting from said block, and a sprocket gear operable within the raceway defined between the walls of the annulus and block having operative connection with said sleeves to impart oscillatory movement to the line shaft and pushers. 85

4. A machine of the character described comprising a sluice having pushers mounted for longitudinal oscillatory movement therein and against the bottom wall thereof, a line shaft, saddle plates horizontally disposed upon said shaft and having trunnions outwardly projecting from the ends thereof, attaching arms carried upon the uppermost inclined ends of the pushers being apertured to accommodate said trunnions, an operating plate having connection with the line shaft including an annular wall upon one side thereof, a block arranged upon the plate and centrally thereof with relation to the adjacent walls of the annulus to define a raceway therebetween, sleeve members arranged at intervals upon the outer exposed face of the block, a retaining plate for the sleeves and projecting for appreciable distances outwardly therebeyond to define a second raceway with relation to said block, and an operating shaft carrying a bearing member and sprocket gear receivable within the respective raceways to facilitate the imparting of oscillatory movement to said plate. 100

In testimony whereof, I affix my signature.

ERVIN E. LINTZ.
